UNITED STATES PATENT OFFICE.

WILLIAM ELMER ETTER, OF BOWER MILLS, MISSOURI, ASSIGNOR OF
ONE-HALF TO P. M. JEWETT, OF CARTHAGE, MISSOURI.

MACHINE-WRENCH.

No. 799,228.

Specification of Letters Patent.

Patented Sept. 12, 1905.

Application filed April 20, 1905. Serial No. 256,638.

To all whom it may concern:

Be it known that I, WILLIAM ELMER ETTER, a citizen of the United States, residing at Bower Mills, in the county of Lawrence and State of Missouri, have invented certain new and useful Improvements in Machine-Wrenches; and I do declare the following to be a full, clear, and exact description of the invention, such as will enable others skilled in the art to which it appertains to make and use the same.

My invention relates to improvements in machine-wrenches of the bolt-holding gear-operating type; and it consists of certain novel features of construction, combination, and arrangement of parts hereinafter described and claimed.

The object of the invention is to provide a simple, comparatively inexpensive, durable, and efficient device or machine of this character which is particularly adapted for use in applying and removing nuts to and from the tire-bolts of vehicle-wheels.

The above and other objects which will appear as the nature of my invention is better understood are accomplished by the construction illustrated in the accompanying drawings, in which—

Figure 1 is a side elevation showing the application of my invention to a portion of a vehicle-wheel. Fig. 2 is a top plan view of the same. Fig. 3 is a vertical transverse sectional view taken on the line 3 3 in Fig. 2 and looking in the direction indicated by the arrow, and Fig. 4 is a vertical longitudinal sectional view taken on the line 4 4 in Fig. 2.

Referring to the drawings by numerals and letters, 1 denotes my improved machine-wrench, which, as seen in Fig. 1 of the drawings, is applied to a portion of a wheel W, comprising a felly F and a tire T, secured upon said felly by tire-bolts B and nuts N. The device 1 is a combined holder and machine-wrench, and it comprises a suitable frame or support 2, which, as shown, consists of a hollow body or sleeve 3, having adjacent to its opposite ends projecting arms or portions 4 and 5, which are adapted to receive a wheel-rim between them. In the portion 4 of the frame is mounted a wrench-shaft 6, which extends through alining bearing-openings 7 formed in the outer end of said portion 4, which is bent upon itself, as shown at 8. Said shaft 6 has in its inner end a nut-socket 9 of square or polygonal

form, and said end has its edge beveled, as shown at 10, to permit the socket to be readily engaged with the nut when the latter is partly or wholly embedded in the felly F of the wheel. In order to protect the felly from being marred by the device, the portion 4 of the frame is formed with inwardly-projecting right-angularly-shaped bracket-arms 11, which are disposed above and below the inner end of the wrench-shaft and which have their inner faces covered with a cushion 12, of leather or the like, which is adapted to contact with the inner face of the felly. These cushion arms or brackets 11 not only protect the felly from being scratched or marred, but also assist in steadyng the frame 2 upon the wheel. The frame is further steadied upon the wheel and prevented from slipping by the provision of a bar 13, which has at its ends set-screws 14, adapted to engage the side edges of the tire T. This bar 13 is slidably mounted upon the sleeve 3 and is adjustably secured thereon by means of a set-screw 15. The adjusting-screws or set-screws 14 are provided in threaded openings in the projecting ends or arms of said bar, and they may be adjusted according to the thickness or size of the wheel.

Upon the outer end of the wrench-shaft 6 is swiveled a handpiece or grip 16, by means of which the frame may be readily handled and supported. This handpiece 16 comprises a circular block 17, which has secured upon its inner face by means of screws 18 a disk 19. The swiveled connection of the handpiece to the shaft 6 is preferably effected by heading, as shown at 120, the inner reduced end 21 of said shaft, which projects through a central opening formed in the disk 19. The shaft 6 rotates freely in the bearing-openings 7 and is also adapted to slide therethrough and through a gear wheel or pinion 20, which is disposed between the doubled or bent portion 8 of the arm 4 of the frame 2. The gear 20, however, is keyed, as shown at 21', upon said shaft, so as to rotate with the same and at the same time to permit the shaft to move or slide longitudinally as the nut in its inner end or socket 9 is unscrewed from its bolt. The gear 20 meshes with a similar gear 22 upon one end of a shaft 23. This shaft extends through and rotates in the sleeve 3 and has on its opposite end an operating crank-

handle 24, by means of which the socket-shaft 6 may be rotated by reason of the meshing gear 20 and 22.

In order to hold the tire-bolts while their nuts are being applied or removed, I provide in the arm or portion 5 of the frame 2 a sliding bolt-clamp 25. This clamp comprises a rod 26, which is slidably mounted in an inwardly-projecting socket 27, formed in the portion or arm 5. Said rod 26 consists of an outer cylindrical portion 28 and an inner reduced square or polygonal-shaped portion 29, which terminates in a beveled end or point 30, adapted to engage the end or the notch in the end of a bolt or screw. The squared portion 29 of the rod slides through a similar-shaped opening at the inner end of the socket 27, and surrounding said portion is a coil-spring 31, which is confined between the enlarged portion 28 of said rod and one end of said socket, so as to exert its energy to move or slide the rod 26 outwardly. The said rod is moved inwardly against the tension of said spring and held in engagement with a bolt or screw by means of a spiral-shaped cam 32, which is provided upon the inner face of a disk 33, mounted to rotate upon the sleeve 3. This disk is confined between the end 28 of the rod 26 and an integral arm or bracket 34, which is provided upon the outer end of the portion 5 of the frame, so that when said disk is oscillated by means of the handle 36, provided upon it, the spiral cam 32 will engage and operate the clamping-rod 26, as will be readily understood.

The construction, operation, and advantages of the invention will be readily understood from the foregoing description, taken in connection with the accompanying drawings.

It will be seen that the machine may be readily applied to or removed from a vehicle-wheel and that it may be quickly adjusted for wheels of any size. When it is mounted upon a wheel, as shown in Fig. 1 of the draw-

ings, and the operating-crank is turned in one direction or the other, the nut will be applied to or removed from the bolt according to the direction of rotation of the wrench-socket.

While I have shown and described the preferred embodiment of my invention, it will be understood that I do not wish to be limited to the precise construction herein set forth, since various changes in the form, proportion, and the minor details of construction may be resorted to without departing from the principle or sacrificing any of the advantages of this invention.

Having thus described my invention, what I claim as new, and desire to secure by Letters Patent, is—

A bolt-holding machine-wrench comprising a sleeve, a pair of arms disposed opposite each other and secured to the sleeve, a longitudinally-movable wrench-shaft having its bearings in one of said arms, a gear splined on the wrench-shaft, and bearing against the outer side of said arm, the latter having a device to prevent outward movement of the said gear on the said shaft, a longitudinally-movable, non-revolute clamping-rod mounted in the other arm, a bracket extending outwardly from said arm and terminating at a point opposite and spaced from the clamping-rod, a spring to press the clamping-rod outwardly, a shaft revoluble in said sleeve, a gear on said shaft engaging the first-mentioned gear, and a revolute cam mounted on said shaft, bearing against the stop formed by the bracket and having on its inner side a concentric wedge-face engaging the outer end of the clamping-rod, substantially as described.

In testimony whereof I have hereunto set my hand in presence of two subscribing witnesses.

WILLIAM ELMER ETTER.
